WELL CLEANING SYSTEM

John Grant, Los Angeles, Calif.

Application June 17, 1935, Serial No. 26,916

6 Claims. (Cl. 166—19)

This invention deals generally with well cleaning systems, particularly of the type wherein there is utilized a device provided with a low pressure or charge receiving chamber having a normally closed inlet adapted to be opened at a predetermined point in the well, whereby the well fluid, under relatively high pressure, charges the chamber with sand or other foreign matter adjacent the inlet, or sets up such pressure actions or high velocity fluid movements as to dislodge foreign matter which may be offering obstruction to free passage of fluid through fissures in the formation or perforations in the well casing. The invention will here be described as applied to the cleaning of casing perforations, to which use it is particularly well adapted, but this particularized description is not to be considered as in any way limitative on the adaptability of the invention for other well cleaning operations.

The usual type of well cleaning device may be described generally as consisting of relatively moving parts, one of which is adapted to engage and remain substantially stationary relative to the casing, and the other part, which usually contains the charge receiving chamber, being movable relative to the part being retained in engagement with the casing. The charge receiving chamber is rendered more or less suddenly communicable with the well fluid by providing a closure adapted to be opened as a result of relative movement between the cleaner parts to which I have referred. Briefly, in a well cleaning operation in which this customary type of cleaner is used, the well cleaning device, including the assembly of relatively movable parts, is lowered in the well to the depth of the zone to be cleaned, and then the cleaner is operated by way of the suspension means to produce relative movement of the parts to open the charge receiving chamber closure.

The invention differs primarily from the customary practice as mentioned above in that it involves a distinct change in well cleaner construction and, as a result, departure from the general methods heretofore employed. Instead of incorporating in a unitized cleaner construction the two general relatively movable parts referred to above, including a section adapted to engage the casing and perform the function, among others, of an abutment acting to open the charge receiving chamber closure upon relative movement of the other section, I make the abutment entirely separate from the charge receiving section of the cleaner, but yet maintain essentially the same operative relationship between

the two. According to the present system, the casing engaging section, hereinafter referred to as the abutment, is first lowered to the desired depth in the well, separately from the cleaner proper, and the latter is then lowered into engagement with the abutment to open the low pressure chamber closure and perform the cleaning operation. Thereafter, the section of the chamber containing the charge may be removed from the well separately from the abutment, and subsequently run back into the well and the operation repeated as many times as may be desired, without having to remove the abutment. In this manner considerable time may be saved throughout the course of a series of individual cleaning operations. Moreover, the usual liability of accidentally tripping the device to prematurely open the charge receiving chamber is avoided in that by reason of the separate sectional characteristics of the apparatus, by no possibility can the chamber become opened until the section containing the chamber reaches a predetermined position of engagement with the abutment.

All the above and various additional features and objects of the invention will be understood to best advantage from the following detailed description of the invention in one of its typical and preferred forms. Reference is made throughout the description to the accompanying drawings; in which:

Fig. 1 is a general view, mainly in elevation, showing the abutment lowered in the well casing and engaged by a tool for removal from the well;

Fig. 2 is a sectional view showing a typical well cleaning device in engagement and operative relationship with the abutment.

Fig. 3 is a downward continuation of Fig. 2 showing the lower portion of the abutment;

Fig. 4 is a fragmentary view, partly in section, showing the upper charge receiving portion of the well cleaner body;

Figs. 5 and 6 are sectional views taken on lines 5—5 and 6—6 of Figs. 2 and 3, respectively; and

Fig. 7 is an elevation showing a variational form of the invention in which the abutment is suspended in the well on the lower end of a pipe string.

In the drawings, I have indicated at 10 a typical form of abutment, which, as previously mentioned, is adapted to be lowered in the well casing 11 to a predetermined position opposite the particular group of casing perforations 12 to be cleaned. After the abutment has been set in proper position, a suitable well cleaning device, 35

typified by the showing at 13, is lowered into engagement and predetermined operative relationship with the abutment 10, causing the closure means for the charge receiving chamber in the well cleaning device 13 to be opened and a charge of well fluid, together with particles clogging the casing perforations, to be drawn upwardly into the chamber, all in the manner hereinafter described.

10 In its preferred form, the abutment 10 comprises a tubular body 14 made up of sections 14a, 14b and 14c interconnected by couplings 15 and 16. The body 14 carries at least one packer, and preferably a pair of packers 17 and 18, which, as will be understood, may be of any suitable type or construction capable of having substantially fluid tight engagement with the casing 11, and vertically confining the annular space 19 between the body 14 and casing 11. I have here shown packers to be of a solid rubber type having, in the case of packer 17, beveled end portions 17a clamped between couplings 20 and 15 provided with beveled surfaces at 20a and 15a engaging the beveled ends of the packer. As shown in Fig. 3, packer 18 is similarly confined between coupling 16 and a shoe 21 threaded at 22 on the lower end of the body and having a fluid passage 23.

For the purpose of enabling well liquid to be by-passed around the packers as the abutment is raised or lowered in the well, I provide one or more by-pass tubes 24, two being shown typically, extending at their lower ends through bushing 25 which has a flange 25a clamped between the lower end of body 14 and shoe 21, the upper ends of the by-pass tubes being inserted within vertical bores 26 in coupling 20, communicating with the interior of the casing 11 by way of laterally extending bores 27. The by-pass tubes prevent fluid resistance to vertical movement of the abutment in the casing that would otherwise occur, by enabling the well fluid to by-pass from above packer 17 downwardly through tubes 24 and passage 23 as the abutment is raised, and in a reverse direction while the abutment is being lowered.

As will later appear, the typical form of well cleaning device here illustrated is adapted to be operated to open communication between the charge receiving chamber and the interior of abutment 10, by virtue of relative vertical movement between the cleaning device and abutment after they have come into engagement. In order to provide for such relative movement, it is desirable that the abutment be held against substantial vertical movement in the casing, and for this purpose I have provided on the abutment a suitable retaining means capable of engaging the casing with sufficient tightness to operate the cleaning device, but permitting the abutment to be lowered into and withdrawn from the casing. The typical form of retaining means illustrated comprises a plurality of radially compressible, bowed spring elements 28 fastened at their ends to sleeves 29 surrounding the body 14 at spaced points between couplings 15 and 16. One or both of the sleeves 29 may be capable of movement longitudinally of the body to permit radial flexing of the spring elements 28.

70 The intermediate section of the body between the packers 17 and 18 is also provided with a series of apertures 30 through which the cleaning device 13 acts to draw liquid from space 19 into the body passage 31 and thence upwardly 75 through vertical bores 32, see Fig. 5, into the

charge receiving chamber D of the cleaning device. Coupling 20 of the abutment carries an upward tubular extension 33 adapted to receive the lower end of the cleaning device 13, there preferably being provided with tube 33 a suitable form of packing or sealing means acting to maintain the abutment and cleaning device in substantially fluid tight engagement. As typical of such sealing means, I show a tubular rubber insert 34 within the lower portion of tube 33 and 10 having a flange 34a clamped between the lower end of the tube and the base of counterbore 35 of coupling 20. For the purpose of facilitating removal of the abutment from the well, I may provide on its upper end a suitable attachment 15 that is readily engageable and retained by, for example, a fishing tool to be lowered in the well. Such attachment may consist, typically, of a socket 36 threaded on the upper end of tube 33, and having a downwardly angular shoulder 37 20 adapted to be engaged by the spring fingers 38, see Fig. 1, of a fishing tool 39 lowered on cable 40.

As I have previously stated, the illustrated form of bailer or cleaning device 13 is to be regarded merely as typical of a variety of such devices capable of cooperation with the abutment to perform the cleaning operation as hereinafter described, and therefore the invention is not to be regarded as limited by the showing of the specific form illustrated. Body portion 30 41 of the cleaning device comprises a series of threadably connected sections 42, 43 and 44, section 42 (Fig. 4) serving as a head or top closure for the low pressure or charge receiving chamber D. Attachment section 45 connected to section 42 serves as a means whereby the body may be attached to a suspension element, as for example cable 46. Section 43, here shown as longitudinally contracted, may be of any desirable length, although a 40 ft. length gives chamber 40 D a capacity ample for most operations.

Section 42 has a reduced axial bore 47 from which extends a transverse passage 48 controlled by a spring closed, outwardly opening relief valve generally indicated at 49. The function of this valve is merely to relieve high pressure in the charge receiving chamber as the tool is raised into zones of lower pressure. To facilitate unloading of chamber D, I preferably provide an inwardly opening, spring closed dump relief valve at 50. This valve is fully described in the copending application of Weldon C. Erwin, et al, on Well Bailers, filed April 22, 1933, Ser. No. 667,439 now Patent No. 2,059,629, granted November 3, 1936. It will suffice here to state that removable screw plug 51 normally closes passage 52 and that when chamber D is to be unloaded, plug 51 is removed so that valve 50 may open to relieve the lowered pressure in the chamber (caused by dumping the fluid) by bleeding air 60 in through a passage 20.

A removable dump door 52 is provided in section 44 of the body, the construction and mounting of this door being fully described in said copending application, Ser. No. 667,439, and requiring for present purposes no further description other than to mention its removability to dump the charge from chamber D following a cleaning operation and after the device has been elevated to the ground surface. Screwed into 70 and depending from section 44 is a tubular section 53 which may be considered a part of the body 41 or as an extension thereof. Seating on the upper end of section 53 is a foot valve 54 which raises to permit the upward flow of the 75.

charge into chamber D, and thereafter seats to trap the charge in the chamber for removal from the well. Charge receiving chamber D is normally closed at its lower end by a frangible disk 55 clamped between a disk carrying member 56 and bushing 57 inserted within bore 58 of section 53.

Carried within the lower end of the cleaner body is a disk breaking member 155 in the form 0 of a tubular plunger capable of limited vertical movement within section 53. Provision is made for such relative movement by a pin and slot connection at 156 between member 155 and the body, pin 157 terminating in body section 53 and 5 extending through vertical slots 158 in opposite sides of the disk breaking member. The lowermost position of member 155 relative to the body is limited by the engagement of the upper end of slot 158 with pin 157; the uppermost such 0 relative position of member 155 being limited, after the disk 55 is broken, by engagement with body shoulder 59.

Tubular shoe 60 is threaded at 61 into the lower end of the disk breaking member 155, the shoe 5 carrying a packing ring 62 confined between shoulder 60b and the lower end of member 155. The diameter of shoe 60 is such that the shoe will have a sliding fit within the abutment liner 34 when inserted therein as shown in Fig. 2, so 0 that between the liner and packing ring 62 there will be a substantially fluid tight fit, thereby preventing any appreciable portion of the charge to be taken into chamber D from being drawn in through the space 64 between the cleaner and 5 abutment section 33.

In performing a cleaning operation, the abutment 10 is first lowered or pushed down within the casing to the depth of that particular portion of the casing to be cleaned. The abutment may be thus lowered in any suitable manner, as for example by pushing it ahead of a weighted body (not shown) lowered on the end of a cable. After the abutment has been placed, the lowering means is withdrawn and the cleaning device 13 lowered on cable 46 into the casing. Upon coming into engagement with the upper end of the abutment, the lower end of the cleaner 13 is guided into tubular portion 33 by the inclined surfaces 37a and 37b within socket member 36. The shoe 60 enters packing liner 34 (the upper end of which is beveled at 34b to insure entry of the cleaner shoe) and moves down into engagement with the end of bore 35 in the coupling 20. While the cleaner 13 is being lowered, disk breaking member 155 and the shoe 60 are supported by pin 157, the latter being in engagement with the upper end of slots 158.

After shoe 60 seats within the abutment in the position illustrated, the body portion 41 of the cleaner continues its downward movement, dropping disk 55 against the upper toothed end 155a of the breaking member, pin 157 having sufficient downward travel within slots 158 to allow member 155 to penetrate and break the disk. Preferably the cleaning device 13 will be lowered rapidly within the well so that after downward movement of the disk breaking member 155 has become arrested, the disk 55 will be impacted against its upper end with sufficient force to break the disk. It is of course apparent that if the disk fails to break, the cleaning device may be withdrawn from the abutment and again dropped into engagement therewith, in the manner explained, until the disk is broken.

Immediately upon breaking the disk, a sudden

pressure differential is imposed between the outside and inside of the casing between packers 17 and 18, with the result that there occurs a sudden rush of well fluid through the casing perforations 12, acting to dislodge and carry into space 19 particles clogging the perforations. The fluid is thence drawn through the abutment body openings 30 into passage 31 and thence upwardly through bores 32, 60a, the interior of the disk breaking member 155, and past valve 54 into the charge receiving chamber D. After the full charge has been taken in and a substantial pressure balance exists between the chamber D and the formation pressure acting to flow the charge into chamber, valve 54 seats to trap the charge 15 in the cleaning device. The latter then is withdrawn from the well and the charge dumped in the manner previously explained. After a new disk 55 has been placed in the cleaning device, the latter may be again lowered to perform another cleaning operation with the abutment 10 remaining in substantially the same position; or after one or a number of individual cleaning operations, the abutment may be shifted vertically within the casing by suitable means manipulated from the ground surface, to bring the abutment opposite a successive section of the casing. At the completion of the cleaning operations, the abutment assembly 10 may be removed from the well by means of suitable tool, such as the fishing tool 39 shown in Fig. 1.

In accordance with the method as described in the foregoing, the abutment used has been separated and disconnected from any suspension or lowering means other than those required for the initial lowering, final removal, or vertical adjustment. If desired, however, the abutment may be lowered on the end of a pipe string, as indicated in Fig. 7, wherein the upper section 33' of the abutment 10' is shown to be coupled at 70 to the lower end of the pipe 71. In this instance the abutment is supported and lowered on the pipe string to the section of the casing to be cleaned, and the cleaning device 13' is lowered within the pipe. The construction of the abutment and cleaner assembly is the same as in the previously described combination except that here, since the abutment is supported on the pipe string, spring elements 28 may be dispensed with, as well as socket 36 on the upper end of section 33'.

I claim:

1. Well cleaning apparatus, comprising a self-contained abutment adapted to be lowered into and retained in engagement with the well casing at any predetermined level, said abutment having a packer making substantially fluid tight engagement with the casing and having a well-fluid passage leading from a point at one side of the packer to a point above the packer at the upper end of the abutment; and a cleaning device adapted to be lowered and raised in the well independently of the abutment, said device having a low pressure chamber with an inlet passage, and a closure normally closing said inlet passage; cooperating means on the abutment and cleaning device to interconnect the abutment passage with the chamber inlet passage when the cleaning device is lowered into contact with the abutment; and means operable by virtue of said contact to open the chamber inlet closure.

2. Well cleaning apparatus comprising a self-contained abutment adapted to be lowered into and retained in engagement with the well cas-

ing at any predetermined depth, said abutment comprising a tubular body, a pair of packers carried at longitudinally spaced points on said body, there being fluid passing apertures in the body between said packers, and means on said abutment adapted to engage a separate and subsequently lowered cleaning device in a predetermined relation.

3. In well cleaning apparatus, the combination comprising, a self contained tubular abutment adapted to be lowered into and retained in engagement with the well casing at any predetermined depth, a separate well cleaning device adapted to be subsequently lowered in the well into engagement with said abutment, said device including a body having a low pressure chamber and normally closed means adapted to be opened to admit well fluid to said chamber, and cooperating means on said body and abutment for opening said means, the last mentioned means including means for restricting the flow of well fluid between said cleaning device and abutment into said chamber.

4. In well cleaning apparatus, the combination comprising, a self contained tubular abutment adapted to be lowered into and retained in engagement with the well casing at any predetermined depth, a separate well cleaning device adapted to be subsequently lowered in the well into engagement with said abutment, said device including a body having a low pressure chamber and normally closed means adapted to be opened to admit well fluid to said chamber, and cooperating means on said body and abutment for opening said means by virtue of impacting movement of said body downward against the

abutment, the last mentioned means including means for restricting the flow of well fluid between said cleaning device and abutment into said chamber.

5. Well cleaning apparatus comprising a self contained abutment adapted to be lowered into and retained in engagement with the well casing at any predetermined depth, said abutment comprising a tubular body, a pair of packers carried at longitudinally spaced points on said body, there being fluid passing apertures in the body between said packers, yielding means holding said body in engagement with the casing, and means on said abutment adapted to engage a separate and subsequently lowered cleaning device in a predetermined relation.

6. In well cleaning apparatus, the combination comprising, a self contained tubular abutment adapted to be lowered into and retained in engagement with the well casing at any predetermined depth, said abutment comprising a tubular body, a pair of packers carried at longitudinally spaced points on said body, there being fluid passing apertures in the body between said packers, a separate well cleaning device adapted to be subsequently lowered in the well into engagement with said abutment, said device including a body having a low pressure chamber and normally closed means adapted to be opened to admit well fluid to said chamber, and cooperating means on said body and abutment for opening said means, the last mentioned means including means for restricting the flow of well fluid between said cleaning device and abutment into said chamber.

JOHN GRANT.
